CLAIM

The ornamental design for a combined flower shaped brush and liquid soap dish, as shown and described.

DESCRIPTION

FIG. 1 is a front view of a combined flower shaped brush and liquid soap dish in accordance with my new design;

FIG. 2 is a rear view thereof; and,

FIG. 3 is a perspective view thereof.

The broken line showing of the bristles and suction cup interior seen in the drawings are included for the purpose of illustrating portions of the combined flower shaped brush and liquid soap dish that form no part of the claim.
